UNITED STATES PATENT OFFICE

117,574

DESIGN FOR A LAMP OR SIMILAR ARTICLE

Albert H. Murray, Buffalo, N. Y.

Application August 26, 1939, Serial No. 86,909

Term of patent 3½ years

To all whom it may concern:

Be it known that I, Albert H. Murray, a citizen of the United States, resident of Buffalo, in the county of Erie and State of New York, have invented a new, original, and ornamental Design for a Lamp or Similar Article, of which the following is a specification, reference being had to the accompanying drawing, forming part thereof.

Fig. 1 is a front elevational view of a lamp, showing my new design;

Fig. 2 is a bottom plan view with the standard in section taken along the line 2—2 of Fig. 1;

Fig. 3 is a top plan view; and

Fig. 4 is a side elevational view thereof.

I claim:

The ornamental design for a lamp or similar article, substantially as shown.

ALBERT H. MURRAY.
